UNITED STATES PATENT OFFICE

OLOF W. ARVIDSON, OF ASHTABULA, OHIO

ORNAMENTAL STRUCTURE

Application filed August 24, 1928. Serial No. 301,787.

This invention relates to ornamental structures for decorative purposes, and more particularly to the provision of a multi-pointed star having a body portion, and a plurality of points secured to the body and radiating therefrom in different lateral planes.

The primary object of the invention is the provision of an ornamental form such as described, wherein the points may be easily attached to and detached from the body portion, as desired.

Another object of the invention is of the production of a body portion and points so designed as to permit compact nesting of the sections of the body portions, and of the star points, one within the other, preparatory to shipment in commerce.

Still another object of the invention is the adaptation of the ornamental form as a covering for lights, or as a light carrier, rendering it especially attractive as a Christmas tree appurtenance.

Other objects of the invention will be made apparent in the following specifications when read in connection with the drawings forming a part thereof.

In said drawings:

Fig. 1 is a side elevation of a star-shaped figure, having twelve points, embodying my invention.

Fig. 2 is a perspective view of one of the star points.

Fig. 3 is a perspective view, partly fragmentary, showing the two sections of the body portion of the ornament.

Fig. 4 is a reduced detail, showing a fragment of the connected sections of the body portions.

Fig. 5 is a top plan view of one of the sections of the body, showing several of the points secured thereto.

Fig. 6 is a side view of the body, showing the means for securing said portions together, and,

Fig. 7 is a top plan view looking down on one section of the body portion.

Now referring specifically to the drawings, in which like reference numerals indicate like parts throughout the several views, 1 and 2 indicate the two sections of the body portion

of the star, and 3 indicates the points, all of which are substantially of the same formation, except as hereinafter noted.

The body sections 1 and 2 are of identical formation, each forming one-half of a pentagonal dodecahedron, the free edges of the sections being regularly serrated to provide hills 4, each provided with an apex 5, and valleys 6, for interfitting engagement with similar hills and valleys on the other section, as clearly illustrated in Figs. 3 and 6. The sections 1 and 2, and the points 3, may be made up of thin sheet metal, of properly stiffened paper, or of any other suitable material, but, in any event, the apex 5 of each hill 4 is adapted to fit under an apron 7, provided at the base portion of each valley 6. If paper is the material used, the apex 5 of the hill 4 may be formed of a commercial paper containing a wire of soft metal, whereby to permit flexure of the apex and properly retain it under the metal, in the position illustrated in Figs. 4 and 6.

As herein illustrated, each of the body sections 1 and 2 is provided with six flat, pentagonal faces lying in different planes, and at about the longitudinal center of the line of juncture between each of the faces, is formed an elongated slot 8, adapted for utilization in securing the points 3 to the body, as will be explained later.

The star points may be made from the same or different material from that of the body portion, as desired, it being understood that they should be of shell-like structure and preferably of conical shape and provided with five flat sides, as herein illustrated. The peripheral edge of the base of the points 3 is of course constructed of five equal sides 9, see Fig. 2, each provided with a bendable tongue 10, adapted to register with and fit into the slot 8 formed in the sections 1 and 2 of the body portion.

Two of the points 3 are very slightly truncated at the extreme end, as illustrated in Fig. 1, all the points being otherwise of identical formation, the purpose of the truncated ends being to provide an aperture in the ends of two oppositely positioned points, for purpose of assembly. In assembling the star, a trun-

cated point 3 is secured to the top pentagonal face 11 of the body section 1, and to the bottom face 12 of the section 2, by inserting the tongues 10 into the slots 8 in the separated body sections, and then bending the tongues out of normal alignment, as shown in Fig. 5. Other points 3 are similarly secured to all the other flat faces of the sections, and a connecting rod 13 is then inserted downwardly through the apertured ends 14, 15 of the oppositely disposed truncated points, passing through centrally positioned apertures provided in the top and bottom flat faces 11 and 12 of the sections 1 and 2. The rod 13 is preferably provided with a looped head 16, and with a screw-threaded lower end 17 adapted to a threaded nut 18. In this position of adjustment, the apices 5 on the sections 1 and 2 are all pressed under the aprons 7 spanning the lower portions of the valleys 6, and the nut 18 is screwed inwardly upon the rod 13 to tightly retain the sections 1 and 2 in their adjusted positions. In disassembling the structure the operation is of course simply reversed.

The body sections 1 and 2 are here illustrated as provided with a plurality of apertures 19, adapted for the passage of electrical connections, when it is desired to illuminate the inside of the ornament, or to attach lights to the apices of each of the points. In such latter case the points 3 might then all be apertured at the extreme end.

In packing the units for shipment the body sections are nested one within the other, as are also the twelve points, thereby permitting a compact wrapping greatly facilitating shipping with reduction of expense.

It is clearly obvious that many modifications of the structure herein disclosed may be suggested to those skilled in the art, and it is understood that the invention covers all embodiments falling fairly within the scope of the appended claims. For instance the points might be made of metal and provided with panels made of glass or other transparencies permitting the passage of light. Or the points might be made of transparent or opaque material, and provided with securing clips. Obviously, also, the star ornament might be made up to provide detachable star points 3 in greater or less numbers.

I claim:

1. An ornamental form comprising a two-part body portion means for detachably securing the sections together, a plurality of star points, and means for detachably securing said points to said body portion.

2. An ornamental form comprising a two-part body portions means for detachably sections of said body portion together, a plurality of star points, means for detachably securing said points to said body portions, and means for retaining said sections and said points in assembled relation.

3. An ornamental structure comprising a base shaped to the form of a pentagonal dodecahedron, and a star point detachably secured to each face of said base.

4. An ornamental structure comprising a base embodying two sections, each formed in the shape of one-half of a pentagonal dodecahedron, means for detachably securing a star point to each surface of said sections, and means for clamping said sections together.

5. An ornamental structure comprising a base embodying two sections, each formed in the shape of one-half of a pentagonal dodecahedron, means for detachably securing a star point to each surface of said sections, and means for clamping said sections together, said means comprising a member extending longitudinally through oppositely positioned star points and through said sections, and adapted to constantly press said sections one against the other.

6. An ornamental form comprising a star composed of a two-sectioned base, a plurality of star points detachably secured to the sections of said base and radiating in different planes, and means for clamping the sections of said base together.

7. An ornamental form comprising a star composed of a two-sectioned base, a plurality of star points detachably secured to the sections of said base and radiating in different planes, and means for clamping the sections of said base together, said means comprising a member extending through said sections and through oppositely positioned star points, said member being provided with means for adjustably imparting pressure upon the ends of said points to compress said sections together.

8. A new article of manufacture consisting of a star ornament comprising a base having twelve flat surfaces facing in different directions, and a star point detachably secured to each of said faces.

9. An ornamental star base having twelve flat surfaces each facing in a different direction, in combination with star points adapted for detachable connection with said base.

10. A fabricated structure comprising a star having a base, and twelve star points secured to said base and each pointing in a different direction and located in a plane different from the plane of any other point.

In testimony whereof I affix my signature.

OLOF W. ARVIDSON. 120
